BLISTER DISPLAY CARD

Mel Appeal, Livingston, and Martin Schnur, West Orange, N.J., assignors to Elpo Industries Inc., Fair Lawn, N.J., a corporation of New Jersey

Filed Mar. 26, 1968, Ser. No. 11,141

Term of patent 14 years

U.S. Cl. D9—192

Int. Cl. D9—04

FIG. 1

FIG. 2

FIGURE 1 is a front elevational view of a blister display card, showing our new design, the reverse side thereof being of like configuration without ornamentation;

FIGURE 2 is a right side elevational view thereof, the left side being substantially a mirror image thereof.

The dominant features of the design reside in the full line portions of the drawing, the conventional wording and blister being shown in broken lines, and the broken line showing of the utensil being for illustrative purposes.

We claim:

The ornamental design for a blister display card, as shown and described.
